UNITED STATES PATENT OFFICE.

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

REGENERATIVE HEATING STRUCTURE.

Application filed February 23, 1923. Serial No. 620,572.

This invention comprehends improvements in regenerative heating apparatus generally and relates particularly to apparatus that is especially adapted for distilling carbonaceous materials. The invention has for an object the provision of a construction that is thoroughly efficient in operation and which will produce high grade coke, when employed for distilling coal, and effect a substantially complete by-product recovery by a distilling operation conducted with great conservation of heat.

Important characteristics of the invention are: the provision of a system of combustion in the flame or combustion flues of the heating walls of the distilling chambers, by which system flame or combustion is maintained concurrently in all of the flues of each heating wall, with periodic reversal in direction of flow of the heating gases and the attainment of efficient combustion and heating effects in each direction of the flow of the heating gases, and with substantially direct connections between a complete reversible regenerative system and both the upper and lower ends of the vertical flame flues, such connections eliminating any necessity for the employment of gas-flow distributing channels between the regenerators and the horizontal or bus-flues that are located at the upper and lower ends of the flame flues; the construction and arrangement of the regenerative system and connection of the same with the flues in such manner as to attain great efficiency in heat conservation and equality in distribution of the heating effect in the several distilling chambers of the battery; a ready adaptability for operation with an extraneously derived gas such as producer gas or blast furnace gas, for fuel, with regenerative heating of the flue gas in some of the regenerators without any countercurrent flow between the incoming fuel gas and the outflowing waste gas, so that waste of the fuel gas is avoided.

In addition to the general objects recited above, the invention has for further objects such other improvements and advantages in construction and operation as are found to obtain in the structures and devices hereinafter described or claimed.

In the accompanying drawings forming a part of this specification and showing, for purposes of exemplification, a preferred

form and manner in which the invention may be embodied and practiced, but without limiting the claimed invention to such illustrative instance or instances:

Figure 1 is a composite vertical sectional and elevational view of a vertical retort construction embodying features above specified and constructed in accordance with the improvements of the present invention, the view being taken in the several vertical planes indicated by the lines C—C, D—D, E—E, and F—F of Figs. 2, 3 and 4;

Fig. 2 is a vertical sectional elevation of the retort construction taken in a plane indicated by the line A—A of Fig. 4;

Fig. 3 is a vertical sectional elevation of the retort construction taken in a plane indicated by the line B—B of Fig. 4; and

Fig. 4 is a composite horizontal sectional view taken in the different horizontal planes indicated by the lines H—H and G—G of Figs. 1, 2 and 3.

The same characters of reference designate the same parts in each of the several views of the drawings.

In its present embodiment, the invention is incorporated in a vertical retort construction for producing metallurgical coke and one that is especially designed for the employment of an extraneously derived gas, such as producer gas or blast furnace gas, for fuel. For convenience, the present description will be confined to this embodiment of the invention; features of construction and operation are, however, capable of other valuable applications, for example, to apparatus generally useful in the heat treatment of materials or to constructions embodying the combination principle exemplified in my co-pending application for Letters Patent of the United States for vertical retort battery, filed February 4, 1921, Serial No. 442,357; consequently the invention is not confined in its scope to the specific use and embodiment herein described as an illustrative example.

Referring to the drawings, there are illustrated views of a vertical retort battery of the by-product type, as hereinbefore mentioned. The vertical retort battery embodies in its construction a series of distilling chambers, such as the series 11 of vertical elongated retorts or coking chambers, the retorts of such series being contiguous to intermediate heating walls 12 110

corresponding to the respective series of retorts 11. The heating walls and the retort chambers extend to a great height as compared with their respective widths and the other crosswise dimensions of the retort battery, and the series of retorts with their corresponding intermediate heating walls are, according to the present embodiment of the invention, respectively arranged and extended along one side of the battery assembly, whereas the regenerators extend in series along the other side of the battery assembly, as will hereinafter appear. The heating walls 12 form the side walls of the respective retorts 11, as shown more particularly in Figs. 1 and 3, and the outer ends of the respective retorts as well as the heating walls are reinforced by side refractory walls designated generally by the reference character 15.

The coal to be coked is charged into the upper end of the retorts 11 through the charging holes 23, and the completed coke is discharged through the openings 26 at the bottoms of said retorts. Because of the great height of the retorts as compared with their width and cross-wise dimensions, the retort battery is preferably employed as a continuous vertical retort. When so employed, a continuous feed of carbonaceous material may be maintained through the retorts 11, with continuous discharge of the finished coke from the bottoms of said retorts. If desired a suitable form of coke handling and discharging apparatus may be employed for receiving and handling the coke as it drops from the bottoms of said retorts, for example apparatus such as is shown and described in my prior application for Letters Patent of the United States for regenerative heating structure, filed July 24, 1922, Serial No. 576,985.

The heat for coking the charges of coal in the several retorts 11 is derived from the heating walls 12 corresponding to said retorts. Each heating wall 12 is constituted of a plurality of vertical flame or combustion flues 37 that are operatively disposed in single groups in their respective heating walls. That is to say, all of the heating flues of each heating wall operate concurrently for flow in the same direction; in fact, the flow is in the same direction during a reversal period throughout the entire system of flues of the battery, as will hereinafter appear.

The regenerators 38 are located on that side of the battery opposite from the retorts 11 and heating walls 12 and are separated from said retorts and heating walls by the mediate wall structure 16. As shown in Fig. 3, the regenerators are located in a single series along one side of the battery, with the major vertical planes of the regenerators parallel with the major vertical planes of

the retorts and heating walls. Operatively, the series of regenerators 38 is disposed into two groups R and S, each such group R, S comprising four regenerators taken seriatum, and the regenerators comprising the groups R alternating with the regenerators comprising the groups S. When the several regenerators constituting the group R are operating for inflow, that is to say, for delivering preheated gaseous media to the flues of the heating walls, the several regenerators of the other groups S are operating for outflow to extract heat from the flue gases discharged into the regenerators from the flues. On reversal of the battery, at the end of an operating period determined by practice, the inflow regenerators become outflow regenerators and the outflow regenerators become inflow regenerators.

Each regenerator 38 is preferably a high narrow upright chamber containing open brickwork, commonly called checkerwork and indicated at 40 with a sole channel 41 underneath such checkerwork, the channels 41 forming the soles of such chambers and opening up into the checkerwork. The several regenerators are heated by the hot combustion products that are exhausted from the flame or combustion flues hereinbefore mentioned and then, on reversal, impart such heat to the medium that they feed into these flame flues.

In the operation of the battery, according to the present embodiment of the invention which employs an extraneously derived gas, such as producer gas for fuel, the several regenerators constituting the group R, when in inflow operation, deliver air and fuel gas to the flame flues during the period when the latter are operating for upflow combustion; these regenerators R receive the exhaust gases from the flame flues after reversal, that is to say, during the period when the flame flues are operating for downflow combustion. On the other hand, the several regenerators constituting the group S operate for inflow of air and fuel gas to deliver the same to the flues when the latter are operating for downflow combustion, and the said regenerators S operate for outflow to receive the exhaust gases from the flues during the period when the latter are operating for upflow combustion. This method of operation requires the regenerators R to be connected with the lower ends of the flame flues 37 and the regenerators S to be connected with the upper ends of said flame flues. The several regenerators of each group R and S are constituted of air regenerators A and gas regenerators P, when operating for inflow, and all the regenerators of each group are constituted of waste gas regenerators W when operating for outflow. However, the several regenerators R operate for inflow while at the

same time the several regenerators S operate for outflow and, on reversal of the flow through the flame flues, the several regenerators S are switched to the inflow function 5 while concurrently the other regenerators R are switched to the outflow function.

In accordance with the invention, and as shown in Fig. 1, the producer gas regenerators P of each group R or S are constituted 10 of the two inside regenerators of their respective groups; whereas the air regenerators A of the groups R and S are constituted of the two outside regenerators of their respective groups. Inasmuch as the groups 15 R alternate with the groups S and when the regenerators of the groups R are operating for inflow, several regenerators of the group S are operating for outflow, and vice versa, and because of the arrangement of the inflow fuel gas regenerators as the inside regenerators of their respective groups, only 20 the air regenerators A of the inflow groups will be adjacent to and in countercurrent relation with the waste gas regenerator W, 25 whether the group R or S be operating for inflow. Consequently any countercurrent relation of flow between adjacent regenerators, in any operation of the battery, is only 30 between air and waste gas regenerators and never between waste gas and fuel regenerators, with the result that there is practically 35 no liability for the fuel gas to become short circuited and pass into the waste gas regenerators, where it would be wasted. 40 The present grouping of the inflow fuel gas regenerators to avoid this countercurrent relation with the waste gases flowing out through the waste gas regenerators is an important advantage because it practically 45 eliminates any waste of fuel gas, inasmuch as the fuel gas regenerators are located remotely from any region where conditions of pressure differential must be maintained in the operation of the battery. The operating 50 conditions in regenerative heating structure practice require a pressure in the outflow regenerators somewhat less than that of the inflow regenerators and, in the construction of the present invention, only 55 the inflow air regenerators are exposed to any losses which might accrue due to this pressure differential. In the case of the incoming air, however, any loss from short circuiting into the waste gas regenerators is 60 practically negligible in the economy of the battery operation.

The several regenerators A of the groups R lead at their upper ends into vertical feed channels 53. These vertical feed channels 60 53 extend down to a level just above the lower ends of the flame flues 37 and there communicate with forked ducts 54, one fork of each duct 54 being connected with the horizontal flue 55 of a heating wall and the 65 other fork of said duct being connected with

the corresponding horizontal flue of an adjacent heating wall. With this construction, each regenerator A of the groups R is connected with the lower ends of the flame flues 37 of a pair of adjacent heating walls, 70 and all the flame flues of the battery are thus provided with direct connections with regenerators that supply air to the flues, whenever upflow combustion is maintained in the flues. The horizontal flues 55 extend beneath and are directly connected with the lower ends of the flame flues 37. 75

The several regenerators P of the groups R lead at their upper ends into vertical feed channels 63. These vertical feed channels 80 63 extend down to a level just below the lower ends of the flame flues 37 and there communicate with forked ducts 64, one fork of each duct 64 being connected with the horizontal flue 65 of a heating wall and the 85 other fork of said duct being connected with the corresponding horizontal flue of an adjacent heating wall. With this construction, each regenerator P of the groups R is connected with the lower ends of the flame flues 90 37 of a pair of adjacent heating walls, and all the flame flues of the battery are thus provided with direct connections with regenerators that supply fuel gas to the flues, whenever upflow combustion is maintained 95 in the flues. The horizontal flues 65 extend beneath and are directly connected with the lower ends of the flame flues 37.

The several regenerators A of the groups S lead at their upper ends into forked 100 ducts 74, one fork of each duct 74 being connected with the upper horizontal flue 75 of a heating wall and the other fork of said duct being connected with the corresponding horizontal flue of an adjacent heating wall. 105 With this construction, each regenerator A of the groups S is connected with the upper ends of the flame flues 37 of a pair of adjacent heating walls, and all the flame flues of the battery are thus provided with direct 110 connections with regenerators that supply air to the flues, whenever downflow combustion is maintained in the flues. The horizontal flues 75 extend above and are directly 115 connected with the upper ends of the flame flues 37.

The several regenerators P of the groups S lead at their upper ends into forked 120 ducts 84, one fork of each duct 84 being connected with the upper horizontal flue 85 of a heating wall and the other fork of said duct being connected with the corresponding horizontal flue of an adjacent heating wall. 125 With this construction, each regenerator P of the groups S is connected with the upper ends of the flame flues 37 of a pair of adjacent heating walls, and all the flame flues of the battery are thus provided with direct connections with regenerators that supply fuel gas to the flues, whenever down- 130

flow combustion is maintained in the flues. The horizontal flues 85 extend above and are directly connected with the upper ends of the flame flues 37.

5 Extending longitudinally of the battery is a waste gas tunnel or stack flue 86, the waste gas tunnel 86 serving for either of the groups R or S of regenerators, when operating as waste gas generators for the 10 outflow of the waste gases. The said waste gas tunnel 86 leads to the usual waste gas stack. There are provided the usual flow boxes for controlling the flow between the waste gas regenerators and said tunnel 86, 15 as well as lids for admitting air to such of the regenerators as are supplying air to the flues. A fuel gas main is also provided with individual valve connections to the several regenerators P of both groups R and S. 20 The control of the flow of the waste gas, the fuel gas and the air may conveniently be effected by mechanism such as is shown and described in my said prior application Serial No. 576,985.

25 The operation of the retort battery, assuming that a relatively lean or dilute gas, such as ordinary producer gas, is employed as the fuel in the flues of the heating walls, is as follows: If it be assumed that the several regenerators comprising the groups R be operating for inflow and that the flues throughout the battery be operating for up-flow combustion. It follows that during this period the regenerators P of the groups 30 R are employed for preheating the fuel gas which is subsequently introduced into the flues. The regenerators A of the groups R are employed for preheating the air to support the combustion of the gas in the flues. 35 Concurrently, all the regenerators of the groups S operate for cutflow, or as waste gas regenerators W. The air and fuel gas passes upwardly through the regenerators A and P of the groups R, thence downwardly through the vertical feed channels 53 and 63, thence into the forked ducts 54 and 64 which deliver the air and fuel gas to the horizontal flues 55 and 65. From said horizontal flues 55 and 65 the air and fuel gas 40 pass into the lower ends of the flame flues 37. Passing upwardly through the flues 37, the fuel gas burns in the air supplied from the horizontal flues 55. At the tops of the flues, the waste gases pass out through the upper horizontal flues 75 and 85, thence through the upper forked ducts 74 and 84 which deliver said waste gases into the regenerators 45 of the groups S. Passing downwardly through the regenerators S, the waste gases finally flow into the waste gas tunnel 86. On reversal of the battery, the flow is exactly reversed through the flow passages just described. The regenerators A and P of the group S deliver to the tops of the flues 50 the air and fuel gas and the waste gases

from said flues exhaust from the bottom thereof into the tops of the regenerators of the group R. Flowing downwardly through said regenerators, the waste gases ultimately pass through their open flow boxes into the 55 waste gas tunnel.

The by-products and distillate gases from the several retorts or coking chambers 11 pass out of the tops of said retorts through ascension pipes individual to the respective 60 retorts 11. These ascension pipes carry the distillate and by-products to a collecting main, such as is disclosed in my said prior application, through which main the distillate and by-products may pass to the by-product recovery apparatus.

The invention as hereinabove set forth may be variously embodied within the scope of the claims hereinafter made.

I claim:

1. In a retort battery, in combination: a row of alternate high narrow retort chambers and heating walls therefor forming one side of the battery; a row of high narrow regenerators parallel with and adjacent to the first mentioned row and forming the opposite side of the battery; each of said retort chambers being adapted to receive through its top the charge to be coked and to discharge through its bottom the coked charge; said heating walls being respectively constituted of substantially vertical combustion flues; each of the combustion flues being adapted for alternate upflow and downflow combustion simultaneously in the same direction as in each of the other combustion flues in the same wall therewith; upper pairs of horizontal flues respectively connected with the tops of the combustion flues; lower pairs of horizontal flues respectively connected with the bottoms of the combustion flues; said regenerators being divided into two groups, the regenerators of one group serving the combustion flues for down flow combustion and the regenerators of the other group serving said flues for upflow combustion, each group of regenerators when operating for inflow comprising both fuel gas and air regenerators, the fuel gas and air regenerators of the downflow combustion group being connected respectively by forked duct means located between the row of regenerators and the row of retorts and heating walls with one upper horizontal flue of each of a pair of adjacent heating walls, and the fuel gas and air regenerators of the upflow combustion group being connected respectively by vertical channel and forked duct means located between the row of regenerators and the row of retorts and heating walls with one lower horizontal flue of each of a pair of adjacent heating walls; substantially as specified.

2. In a vertical retort battery, in combination: a row of alternate high narrow retort

- chambers and heating walls therefor forming one side of the battery; a row of regenerators parallel with and adjacent to the first mentioned row and forming the opposite side of the battery; each of said retort chambers being adapted to receive through its top the charge to be coked and to discharge through its bottom the coked charge; said heating walls being respectively constituted of substantially vertical combustion flues; each of the combustion flues being adapted for alternate upflow and downflow combustion simultaneously in the same direction as in each of the other combustion flues in the same wall therewith; upper pairs of horizontal flues respectively communicably connected with the tops of the combustion flues; lower pairs of horizontal flues respectively connected with the bottoms of the combustion flues; said regenerators being divided into two groups, the regenerators of one group serving the combustion flues for downflow combustion and the regenerators of the other group serving said flues for upflow combustion, each group of regenerators when operating for inflow comprising both fuel gas and air regenerators, the fuel gas and air regenerators of the downflow combustion group being connected respectively by forked duct means located between the row of regenerators and the row of retorts and heating walls with one upper horizontal flue of each of a pair of adjacent heating walls, and the fuel gas and air regenerators of the upflow combustion group being connected respectively by vertical channel and forked duct means located between the row of regenerators and the row of retorts and heating walls with one lower horizontal flue of each of a pair of adjacent heating walls; substantially as specified.
4. In a vertical retort battery, in combination: a row of alternate high narrow retort chambers and heating walls therefor forming one side of the battery; a row of regenerators parallel with and adjacent to the first mentioned row and forming the opposite side of the battery; each of said retort chambers being adapted to receive through its top the charge to be coked and to discharge through its bottom the coked charge; said heating walls being respectively constituted of substantially vertical combustion flues; each of the combustion flues being adapted for alternate upflow and downflow combustion simultaneously in the same direction as in each of the other combustion flues in the same wall therewith; said regenerators being divided into two groups, the regenerators of one group serving the combustion flues for downflow combustion and the regenerators of the other group serving said flues for upflow combustion, each group of regenerators when operating for inflow comprising both fuel gas and air regenerators, the fuel gas and air regenerators of the downflow combustion group being connected respectively by forked duct means located between the row of regenerators and the row of retorts and heating walls with the upper ends of the flame flues of a pair of adjacent heating walls, and the fuel gas and air regenerators of the upflow combustion group being connected respectively by vertical channel and forked duct means located between the row of regenerators and the row of retorts and heating walls with the lower ends of the flame flues of a pair of adjacent heating walls; substantially as specified.
5. In a vertical retort battery, in combination: a row of alternate high narrow retort chambers and heating walls therefor forming one side of the battery; a row of regenerators parallel with and adjacent to the first mentioned row and forming the opposite side of the battery; each of said retort chambers being adapted to receive through its top the charge to be coked and to discharge through its bottom the coked charge; said heating walls being respectively constituted of substantially vertical combustion flues; each of the combustion flues being adapted for alternate upflow and downflow combustion simultaneously in the same direction as in each of the other combustion flues in the same wall therewith; upper pairs of horizontal flues respectively connected with the tops of the combustion flues; lower pairs of horizontal flues respectively connected with the bottoms of the combustion flues; said regenerators being divided into two groups, the regenerators of one group serving the combustion flues for downflow

- stituted of substantially vertical combustion flues; each of the combustion flues being adapted for alternate upflow and downflow combustion simultaneously in the same direction as in each of the other combustion flues in the same wall therewith; said regenerators being divided into two groups, the regenerators of one group serving the combustion flues for downflow combustion and
- 10 the regenerators of the other group serving said flues for upflow combustion, the regenerators of the downflow combustion group being connected respectively by forked duct means located between the row of regenerators and the row of retorts and heating walls with the flues at the upper ends of a pair of adjacent flued heating walls, and the regenerators of the upflow combustion group being communicably connected respectively by vertical channel and forked duct means located between the row of regenerators and the row of retorts and heating walls with the flues at the lower ends of a pair of adjacent flued heating walls; substantially as specified.
- 15 8. A vertical retort battery having a row of alternate retort chambers and heating walls therefor forming one side of the battery, said heating walls containing substantially vertical combustion flues; combined with a row of regenerators, parallel with and adjacent to the first mentioned row, forming the opposite side of the battery and disposed in downflow combustion groups alternating with upflow combustion groups, the regenerators of said groups being respectively connected by forked duct means located between the row of regenerators and the row of retorts and heating walls with the flues at the upper and lower ends of pairs of the flued heating walls; substantially as specified.
- 20 9. In a vertical retort battery, in combination: a row of alternate retort chambers and heating walls therefor forming one side of the battery; a row of regenerators parallel with and adjacent to the first mentioned row and forming the opposite side of the battery; said heating walls being respectively constituted of substantially vertical combustion flues; each of the combustion flues being adapted for alternate upflow and downflow combustion simultaneously in the same direction as in each of the other combustion flues, each of said flues being in the same wall therewith; upper pairs of horizontal flues respectively connected with the tops of the combustion flues; lower pairs of horizontal flues respectively connected with the bottoms of the combustion flues; said regenerators being divided into two groups, the regenerators of one group serving the combustion flues for downflow combustion and the regenerators of the other group serving said flues for upflow combustion, each group of regenerators when operating for inflow comprising both fuel gas and air regenerators, the fuel gas and air regenerators of the downflow combustion group being connected respectively by forked duct means located between the row of regenerators and the row of retorts and heating walls with one upper horizontal flue of each of a pair of adjacent heating walls, and the fuel gas and
- 25 6. A vertical retort battery having a row of alternate retort chambers and heating walls therefor forming one side of the battery, said heating walls containing substantially vertical combustion flues; combined with a row of regenerators, parallel with and adjacent to the first mentioned row, forming the opposite side of the battery and disposed in downflow combustion groups alternating with upflow combustion groups, the regenerators of said groups being respectively connected by forked duct means located between the row of regenerators and the row of retorts and heating walls with the flues at the upper and lower ends of pairs of the flued heating walls; substantially as specified.

- air regenerators of the upflow combustion group being connected respectively by vertical channel and forked duct means located between the row of regenerators and the row 5 of retorts and heating walls with one lower horizontal flue of each of a pair of adjacent heating walls; substantially as specified.
10. In a vertical retort battery, in combination: a row of alternate retort chambers 10 and heating walls therefor forming one side of the battery; a row of regenerators parallel with and adjacent to the first mentioned row and forming the opposite side of the battery; said heating walls being respectively constituted of substantially vertical combustion flues; each of the combustion flues being adapted for alternate upflow and downflow combustion simultaneously in the same direction as in each of the 15 other combustion flues, each of said flues being in the same wall therewith; upper pairs of horizontal flues respectively connected with the tops of the combustion flues; lower pairs of horizontal flues respectively 20 connected with the bottoms of the combustion flues; said regenerators being divided into two groups, the regenerators of one group serving the combustion flues for downflow combustion and the regenerators of the 25 other group serving said flues for upflow combustion, the regenerators of the downflow combustion group being connected respectively by forked duct means located between the row of regenerators and the row 30 of retorts and heating walls with one upper horizontal flue of each of a pair of adjacent heating walls, and the regenerators of the upflow combustion group being connected respectively by vertical channel and forked 35 duct means located between the row of regenerators and the row of retorts and heating walls with one lower horizontal flue of each of a pair of adjacent heating walls; substantially as specified.
- 40 45 11. In a vertical retort battery, in combination: a row of alternate retort chambers and heating walls therefor forming one side of the battery; a row of regenerators parallel with and adjacent to the first mentioned 50 row and forming the opposite side of the battery; said heating walls being respectively constituted of substantially vertical combustion flues; each of the combustion flues being adapted for alternate upflow and 55 downflow combustion simultaneously in the same direction as in each of the other combustion flues, each of said flues being in the same wall therewith; said regenerators being divided into two groups, the regenerators of the 60 one group serving the combustion flues for downflow combustion and the regenerators of the other group serving said flues for upflow combustion, each group of regenerators when operating for inflow comprising both 65 fuel gas and air regenerators, the fuel
- gas and air regenerators of the downflow combustion group being connected respectively by forked duct means located between the row of regenerators and the row of retorts and heating walls with the upper ends 70 of the flame flues of a pair of adjacent heating walls, and the fuel gas and air regenerators of the upflow combustion group being connected respectively by vertical channel and forked duct means located between the 75 row of regenerators and the row of retorts and heating walls with the lower ends of the flame flues of a pair of adjacent heating walls; substantially as specified.
12. In a vertical retort battery, in combination: a row of alternate retort chambers and heating walls therefor forming one side of the battery; a row of regenerators parallel with and adjacent to the first mentioned row and forming the opposite side 80 of the battery; said heating walls being respectively constituted of substantially vertical combustion flues; each of the combustion flues being adapted for alternate upflow and downflow combustion simultaneously in 85 the same direction as in each of the other combustion flues, each of said flues being in the same wall therewith; said regenerators being divided into two groups, the regenerators of one group serving the combustion flues for downflow combustion and the regenerators of the other group serving said flues for upflow combustion, the regenerators of the downflow combustion group being 90 connected respectively by forked duct means located between the row of regenerators and the row of retorts and heating walls with the upper ends of the flame flues of a pair of adjacent heating walls, and the regenerators of the upflow combustion group being 95 connected respectively by vertical channel and forked duct means located between the row of regenerators and the row of retorts and heating walls with the lower ends of the flame flues of a pair of adjacent heating walls; substantially as specified.
- 100 105 110 115 120 125 130
13. A vertical retort battery having a row of alternate retort chambers and heating walls therefor forming one side of the battery, said heating walls containing substantially vertical combustion flues; combined with a row of regenerators, parallel with and adjacent to the first mentioned row, forming the opposite side of the battery and disposed in downflow combustion groups alternating with upflow combustion groups, the regenerators of said groups being respectively connected by forked duct means located between the row of regenerators and the row of retorts and heating walls with the upper and lower ends of a plurality of the fluid heating walls and each group of regenerators when operating for inflow comprising both fuel gas and air regenerators, the fuel with the fuel gas regenerators disposed in the

inside of the group and the air regenerators at the outside, whereby countercurrent flow between inflow fuel gas regenerators and outflow waste gas regenerators is prevented; 5 substantially as specified.

14. A vertical retort battery having a row of alternate retort chambers and heating walls therefor forming one side of the battery, said heating walls containing substantially vertical combustion flues; combined with a row of regenerators, parallel with and adjacent to the first mentioned row, forming the opposite side of the battery and disposed in downflow combustion groups 10 alternating with upflow combustion groups, the regenerators of said groups being respectively connected by duct means located between the row of regenerators and the row of retorts and heating walls with the upper 15 and lower ends of a plurality of the flued heating walls; substantially as specified.

15. A vertical battery having a row of alternate retort chambers and heating walls therefor forming one side of the battery; 20 said heating walls respectively comprising substantially parallel combustion flues; combined with a row of regenerators, parallel with and adjacent to the first mentioned row, which forms the opposite side of the battery 25 and which are divided into two groups and which are respectively connected by forked duct means located between the row of regenerators and the row of retorts and heating walls with one end of the flues of a plurality of the heating walls; substantially as 30 described.

16. A retort battery with a row of alternate vertically operable retorts and vertically flued heating walls therefor forming 35 one side of the battery; a row of reversible regenerators parallel with and adjacent to

the first mentioned row and forming the opposite side of the battery; and ducts, located between the row of regenerators and the row of retorts and having the regenerators disposed in outflow groups alternating with inflow groups and with both the upper and the lower ends of the flues of the heating walls connected by ducts with the regenerators in such a manner that combustion may take place alternately upwardly and downwardly in the vertical flues of all the heating walls in successive working periods; substantially as specified. 45

17. In combination a retort battery comprising a row of alternate coking chambers and substantially vertically flued heating walls forming one side of the battery; a row of regenerators parallel with and adjacent to the first mentioned row and forming the opposite side of the battery; said regenerators being arranged in alternate and intermediate groups, each regenerator of alternate groups communicating through ducts located between the row of regenerators and the row of coking chambers and heating walls with the upper ends, and each regenerator of the intermediate groups communicating through ducts located between the row of regenerators and the row of coking chambers and heating walls with the lower ends of the flame flues of a plurality of said heating walls; substantially as specified. 50

18. A retort battery as claimed in claim 17 in which the upper ends of the regenerators of the intermediate groups communicate with the lower ends of the flues of the heating walls; substantially as specified. 55

In testimony whereof I have hereunto set my hand.

JOSEPH VAN ACKEREN.
